UNITED STATES PATENT OFFICE.

JOHN E. GABLE, OF CAMBRIDGE, AND IRA A. GABLE, OF BYESVILLE, OHIO.

AUTOMATIC CAR-STOP AND CAGING APPARATUS FOR MINES.

1,064,067.

Specification of Letters Patent. Patented June 10, 1913.

Application filed August 18, 1911. Serial No. 644,838.

To all whom it may concern:

Be it known that we, JOHN E. GABLE and IRA A. GABLE, citizens of the United States, residing at Cambridge, in the county of 5 Guernsey and State of Ohio, and Byesville, in the county of Guernsey, State of Ohio, respectively, have invented certain new and useful Improvements in Automatic Car-Stops and Caging Apparatus for 10 Mines; and we do hereby declare the following to be a full, clear, and exact description of the invention, such as will enable others skilled in the art to which it appertains to make and use the same.

15 Our invention relates to mining appliances but has reference more particularly to automatic car-stops and caging-apparatus employed for elevating coal to the surface of mine shafts.

20 The object of the invention is to provide mechanism for automatically releasing the first and each succeeding one of a train of loaded cars, delivering the same upon the floor of a mine cage, elevating it to the 25 surface, and finally discharging the empty cars after they have been returned to the bottom of the shaft.

A further object is that of reducing the 30 number of employees required, safeguarding the lives and limbs of those actually engaged in the several operations aforesaid, and reducing operating expenses.

With these and other objects in view our 35 invention consists in certain novel features and in certain combinations and arrangements of parts which will be hereinafter described and pointed out by the claims following.

In the accompanying drawings which 40 form part of this application, and whereon corresponding numerals indicate like parts in the several views: Figure 1 is a plan view of the discharge end of a pair of tracks leading to the sump at the bottom of a mine 45 shaft, showing one of two cages in its lowermost position. Fig. 2 is a side elevation of parts represented by Fig. 1 and in addition the advance end of one coal car at the instant of its release for delivery to the cage. 50 Fig. 3 is also a plan view of tracks, being a projection or continuation of Fig. 1, including the looped end of a cable common to both track sections for imparting an impetus to the loaded cars when released individually. Fig. 4 is a side elevation of parts disclosed by Fig. 3, showing also a

pair of folding spurs carried by said starting cable for engaging the individual car frames to automatically start them when automatically released. Fig. 5 is a longitudinal section, on the line 5—5 of Fig. 8, through one cage bottom in its lowermost position resting upon positive abutments at opposite sides, and immediately above the shaft sump. Fig. 6 is a view corresponding to Fig. 5, taken on the line 6—6 of Fig. 8, after the cage has commenced its ascent. Fig. 7 is a transverse section through one cage bottom taken on the line 7—7 of Fig. 6, and, Fig. 8 is a plan view of one cage 70 bottom relatively enlarged showing depressible cage track sections. Fig. 9 is a side elevation, partly in section, of a car stop employed for arresting cars in their passage toward the mine cages. Fig. 10 is an end 75 view of parts shown by Fig. 9. Fig. 11 a plan view of said car stop. Fig. 12 is a side elevation of conveying apparatus for advancing cars in their passage to the mine cages. Fig. 13 is a top plan view of parts 80 shown by Fig. 12, and Fig. 14 is an end view of said conveyer apparatus.

Reference being had to the drawings and numerals thereon it will be understood that the framing, of structural iron or other suitable material usually employed in mine shafts, including the vertical guide rails for the ascending and descending cars or cages, is presumed to be present in this. Also that the cars or cages referred to are counterparts one of the other for which reason a description of one will here suffice and apply equally well to both; also that said cages are provided with suitable hoisting appliances of well known construction and therefore not shown, and are, as is ordinarily the case, arranged in counterbalancing relation.

Cages 10 are preferably of skeleton form and mainly of structural iron for lightness and strength of the structure, as best shown 100 by Figs. 5, 6 and 7.

Connecting the front and back uprights or corner posts of cage 10 are channel irons 11, 11 longitudinally arranged at each side; in the same plane are interposed longitudinal I-beams 12, 12, as best shown by Fig. 7, to opposite ends thereof are bolted transverse channel irons 13, 13, said irons and beams constituting the support for the cage floor or platform 14. Upon this floor 14 are secured the end sections of a pair of rails 15, 15 and 16, 16 in proper alignment, while

in the same alinement between said rail sections the floor 14 is slotted as at 17, 17 for purposes which will later appear. By reference to Figs. 5 and 6, more especially, it will be noted that the end rail sections 15, 15 are hinged to platform 14 at their extreme outer ends as at 18, are connected at their inner ends by a cross bar 19 from which depend headed bolts or tie-rods 20, 20 connected reciprocally with a sub-frame of the cage of which a description will follow. The said bolts 20 are surrounded by coil springs 21, 21, which when compressed serve to elevate the innermost or free ends of rail sections 15, 15 as shown by dotted lines in Fig. 5. When normally depressed as represented by Figs. 5, 6 and 7 the said rail sections are securely retained by a keeper 22 depending from the center of cross bar 19, and a spring-pressed horizontally slid able latch 23 carried by the underside of the floor or platform 14. To the downwardly curved tail-stock of said latch 23 is a horizontally and outwardly extending operating link 24 the latter pivotally connected to a short lever 25 carried by a rockshaft 26, also journaled beneath the cage floor, while the opposite end of shaft 26 is upwardly curved, or rigidly connected to a member upwardly curved in the path of a wheel traversing the adjacent track section 15, this for the purpose of automatically withdrawing latch 23 as a car leaves and permitting the track sections to assume their dotted position for purposes which will appear in connection with a statement of operation hereinafter.

Rigidly secured to, and downwardly extending from, the longitudinal side rails or channel irons 11, 11 of the mine cage, are bolts 27 headed at their lowermost ends, upon which are reciprocally suspended a sub cage-frame of skeleton form comprising longitudinally arranged side channel irons 28, 28, corresponding with the said irons 11, 11 immediately above, and reinforced by transverse connecting irons 29 bolted thereto at intervals as best shown by Figs. 5 and 6. Crossing at right angles the said sub-frame members or irons 29 in vertical alinement with slots 17, 17 of the cage floor 14 and of a length to correspond therewith, are I beams 30, 30, upon the upper surfaces whereof are secured rail sections 31, 31 which are therefore vertically movable upon the sub-frame with relation to the cage floor, and are adapted when elevated through slots 17, 17 to register with the end sections 15, 15 and 16, 16 to make a continuous track across said floor. While at both sides of the mine cage is a downwardly projecting V shaped strut 32 rigidly secured at its opposite ends with its inverted apex terminating at a point below the lowermost or normal position of the sub-frame

aforesaid as shown by Fig. 2. At their lowermost points these struts are connected by a cross bar 33 upon which is mounted an enlarged sleeve 34 for purposes hereinafter stated.

Leading to the mine shaft so as to register at times with the tracks aforesaid upon the elevator cage floors are a pair of tracks 35, 35 and 36, 36 of ordinary construction but slightly inclined toward the sump. At a given point upon each track 35 and 36 approximately one car length from the sump are located car stops of novel construction and operation, these also being counterparts one of the other and adapted to automatically first arrest and then release the first car of a train previous to caging same. These stops of which but one will be described, comprise a main rod or bar 37 having an adjusting nut 38 upon the lower end swiveled upon one of the ordinary track crossties, as best shown by Fig. 9. Upon said rod 37 is reciprocally mounted a hollow body member or stop-block 39 having an upwardly projecting wedge-shaped spur 40 for engaging, at times, the advance bumper of a coal car as shown by Fig. 2, while interposed between the lower end of said block 39 and an adjusting nut 41 threaded upon the upper end of bar 37 is an absorption spring 42 for reducing the shock when a car is suddenly arrested. To the uppermost portion of the said stop-block 39 and upon each side thereof are pivotally connected a double toggle lever 43, 43' having their opposite or lower ends keyed upon a rock shaft 44, and so positioned that the links of said toggles slightly pass their centers of attachment when elevated, as shown by full lines. To both ends of said shaft 44 are also securely keyed operating levers 45, 45, from the free ends of which in a horizontal direction project pivotally connected rods 46, 46 which at their opposite ends are again pivotally connected to bell-crank levers 47, 47 journalled as at 48 in fixed supports or journal bearings upon opposite sides of the track as indicated by Fig. 1 of the drawings. It will thus be seen that the shorter members of the said bell-crank levers are located upon the inside, adjacent to the track rails, and in a position to be engaged by the wheels of a passing car to rock said levers upon their pivotal supports.

Upon the same pivots or wrist pins 49, 120 which serve to connect the upper end of levers 47 and their co-operating rods 46 as aforesaid, are slidably secured links 50 terminating in horizontal rods 51 leading to an upright 52 at one side of the elevator or cage shaft. As best illustrated by Figs. 1 and 2 the said rods 51 at their outer ends are pivotally connected to the lower extremity of a T shaped tripper or operating member 53, which in turn is pivotally connected, as at 130

54, to the upright 52 before mentioned and projects at one side of its pivotal connection directly in the path of a stud or actuating pin 55 carried by the inner lower corner of the cage frame 10, as shown by Figs. 1 and 2.

Secured as at 56, 56 to the far side of the shaft sump is a cable 57 which crosses the sump in a position to be engaged by the roller 34 below the mine cages as they descend, and, extending over guide rollers 58 traverse the tracks 35, 36, as indicated by Figs. 1-3, and are looped over horizontal sheaves 59, 59, as represented near the right hand end of the latter Fig. 3. To this cable at points approximating the length of standard coal cars between bumpers and over both tracks 35, 36, are located one or more spurs 60 pivotally connected upon arms 61 secured to said cable in a manner to permit of folding horizontally as a car or cars pass over them, but adapted to resist any back movement of cars once past them. Obviously the said folding spurs 60 may be attached directly to the cable 57, but as illustrated they are preferably secured to arms 61 which in turn are attached to a conveyer 62 through the longitudinal center of which passes the said cable 57, as best shown by Fig. 14. This conveyer 62 is provided with anti-friction rollers or wheels 63 at both ends, located in a trough-shaped guiding and retaining runway 64, by preference made of sheet iron having a closed bottom and sides, also inwardly projecting surface flanges 65, and, as a consequence, a central surface-slot between said flanges through which latter the spurs 60 and their supporting arms 61 project. One of the aforesaid runways 64 is located between the rails of each track as 35 and 36 leading to the sump, where they are securely spiked down. In each are located one or more conveyers 62 equipped as aforesaid, and between the outer end of each conveyer and its adjustable stop 66 upon the cable 57 is a spring 67 surrounding the said cable for absorbing undue shocks when spurs 60 engage a car sill to advance it, as will now appear in a statement of operation.

Presuming that a motor has left a train of uncoupled but loaded cars upon either or both of the inclined tracks 35, 36 ready for delivery to the mine cage or cages, and that, in assuming the position indicated by Fig. 4, the spurs 60 have each been folded down to permit passage of the individual car bodies, but owing to their enlarged overbalanced lower ends, have naturally resumed their vertical or normal position shown by the drawings with the first spur of the series 60 engaging the trailing end of a car frame to one side of its bumper. When in this position it will be noted by reference to Fig. 2, that the advance bumper of the first car to be caged is engaged by the wedge shaped spur 49 of stop-block 39 which retains it se-

curely in position until the opportune moment for its release. With a descending cage 10 now nearing the limit of its downward movement, the actuating pin 55 engages and automatically rocks the T-shaped tripper or operating member 53 upon its center 54 thereby projecting the horizontal rod 51 toward the first of the line of laden cars to be caged, similarly the rod 46 is projected by agency of the wrist pin 49 resting in the outer end of link 50, the lever 45 thrown backward, shaft 44 rocked, toggle 43, 43' lowered, and stop-block 39 depressed, all as indicated by dotted lines in Fig. 9 of the drawings.

At the instant a laden car has been released as aforesaid the continued downward movement of the cage automatically imparts to the car an advance movement toward said cage as follows: Roller 34 engaging slack cable 57 where it crosses the shaft sump, hauls same taut as the cage floor reaches the level of the caging tracks, and as a consequence all conveyers 62 located upon that particular track are advanced slightly by agency of the stops 66 affixed to said cable and the interposed absorption springs 67, with the result that spur 60 engaging the trailing end of the foremost car, released as aforesaid imparts thereto a forward movement which cages it just as the cage floor reaches the limit of its descent and is arrested by the abutments α α (Figs. 5 and 6), or equivalent means, at sides of the shaft. At this stage of the caging operation the floor 14 and sub-frame of the hoisting cage occupy the relative positions shown by Fig. 5, with all rail sections in alinement, but with the outer sections 15, 15 raised as shown by dotted lines to serve in arresting the advancing car when it has reached a position upon the intermediate rail sections 31, 31.

The laden car having been caged as aforesaid, the hoisting is commenced whereupon all cage parts assume the relative positions indicated by Figs. 6 and 7, the sub-frame gravitating to the end of tie rods 20, and with it the intermediate track sections 31, 31 bearing the wheels of the caged car which are thus depressed to their axles through slots 17, 17 in the cage floor proper and securely retained during the hoisting operation. After reaching the tipple (not shown) the car may be dumped in any approved or well known manner, and returned to the bottom of the shaft still supported as aforesaid with its wheels through slots 17, 17 in the cage floor and resting upon the depressed track sections 31, 31. As the sub-frame of the hoisting-cage bottoms upon abutments α , α of the shaft, or their equivalent, it is positively arrested while the superstructure continues its descent until these parts assume the relation indicated by Fig. 130

5 of the drawings with track sections 31, 31, supporting the caged and now empty car, elevated into horizontal alinement with sections 15 and 16 upon the cage floor. At the 10 same time coil spring 21 is automatically placed under tension as the super-frame descends to meet the sub-frame as aforesaid, and it will be noted that the track sections 15, retained normally in a horizontal position by agency of keeper 22 and latch 23, now serve the two-fold purpose of assisting in the discharge of the empty car from the cage, and of arresting the incoming laden car with its wheels upon track section 31, 31. 15 In other words, as the empty car is forcibly ejected from the cage, either automatically or manually, one wheel in passing over the short, curved lever 26' upstanding in its path, depresses the said lever, rocks its connected shaft 26, and throws, in a backward direction, the horizontally reciprocating rod 24 to withdraw latch 23 from its keeper 22 secured to the cross bar 19 connecting the ends of rail sections 15, 15. This accomplished the latter sections immediately assume, under influence of the compressed spring 21, the position indicated by dotted lines in Fig. 5, for the double purpose aforesaid. It will be further noted that a laden 20 car in passing onto the cage floor as hereinbefore described, serves to automatically reset the stop mechanism for arresting and detaining the next succeeding car as follows: In its passage just prior to entering 25 cage 10 the advance car wheels engage and depress the free ends of oppositely disposed track levers 47, 47, throwing the wrist pins 49, 49 to the outer end of links 50, 50, carrying with them the horizontal rods 46, 46, 40 and thus rocking shaft 44 to elevate toggle 43, 43' and reset the stop 40 as indicated by Figs. 2 and 9 to arrest and retain the succeeding laden car or cars until same shall be automatically released as hereinbefore described. This being a general description of our invention it should be understood that we do not confine ourselves to the precise form and arrangement of parts set forth, but on the contrary contemplate various 45 structural modifications and changes in form, arrangement and combination of parts, which are not herein shown and described, but which are plainly within the scope of our invention.

50 Having thus described our invention, what we now claim and desire to secure by Letters Patent is:

1. The combination with an elevating cage of an inclined track leading thereto, a bumper pivotally supported between the rails of said track for arresting cars in their passage to said cage, a toggle-lever for elevating and depressing the operative end of said bumper, a tripper member adapted to be actuated by a passing cage, connections

between said tripper member and said toggle-lever whereby the latter is automatically depressed to inoperative position, and a trip-mechanism adapted to be operated by the passage of a car to said cage for raising said toggle lever and bumper into operative position.

2. The combination with an elevating cage, of an inclined track leading thereto, means for stopping cars in their passage over said track to said cage, means arranged and adapted to be automatically actuated by the movement of said cage for operating said stopping means, and means also automatically actuated by the descending cage 80 for imparting an initial movement to each individual car after its release from the stopping means aforesaid.

3. The combination with an elevating cage, of an inclined track leading thereto, 85 means for stopping the cars in their passage over said track to said cage, means arranged and adapted to be automatically actuated by the movement of said cage for operating said stopping means, and a flexible cable 90 crossing the shaft sump in a position to be engaged by a descending cage and provided with spurs for engaging and imparting an initial movement to each individual car after its release from the stopping means 95 aforesaid.

4. The combination with an elevating cage, of an inclined track leading thereto, means for stopping cars in their passage over said track to said cage, means arranged 100 and adapted to be automatically actuated by the movement of said cage for operating said stopping means, and a flexible cable crossing the shaft sump in a position to be engaged by a descending cage provided with 105 folding and spring-cushioned spurs for engaging and imparting an initial movement to each individual car after its release from the stopping means aforesaid.

5. The combination with an elevating 110 cage, of an inclined track leading thereto, means automatically actuated by passage of the said cage for stopping cars in their passage over said track, means also automatically actuated by the descending cage for imparting an initial movement to each individual car after its release from the stopping mechanism aforesaid, and a system of levers and intermediate connections adapted to be automatically actuated by a car in its passage to 120 the cage for resetting the aforesaid stopping means.

6. The combination with an elevating cage, of an inclined track leading thereto, means automatically actuated by movement 125 of said cage for stopping cars in their passage over said track and for releasing them at predetermined periods, a slack cable crossing the shaft-sump in position to be engaged by the descending cage, and a spur carried 130

by said cable adapted to engage and advance the car to be caged as the slack is removed from said cable by engagement of the descending cage.

5 7. A mine cage comprising a main and a sub-frame relatively movable in a vertical direction, railway track sections at opposite sides of said main frame, and an intermediate track section upon said sub-frame all 10 of said track sections adapted to register and to constitute a continuous track at the instant cars are caged thereon.

8. A mine cage comprising a main and a sub-frame relatively movable in a vertical 15 direction, a car track crossing said cage made up of independent sections of which the end sections are carried by the said main frame and the intermediate section by the de-pressible sub-frame aforesaid.

20 9. A mine cage comprising a main frame, a floor for said main frame, car track sections affixed to said floor at opposite sides of the cage, a sub-frame reciprocally suspended from said main frame, and an intermediate car track section carried by said sub-frame adapted to register with the sections aforesaid when said sub-frame assumes its uppermost position during the caging operation.

25 10. A mine cage comprising a main frame, a floor for said main frame, a car track section affixed to the entering side of said cage floor, a similar track section hinged at the extreme opposite side of said cage floor, a

sub-frame reciprocally suspended from said 35 main frame, an intermediate car track section carried by said sub-frame adapted to register with the sections aforesaid during the caging operation, and means for elevating said sub-frame at the time of caging a 40 car.

11. A mine cage comprising a main frame, a floor for said main frame, a car track section affixed to the entering side of said cage floor, a similar track section hinged at 45 the extreme opposite side of said cage floor, a latch for retaining the last mentioned track section normally in a horizontal position, a latch-withdrawing mechanism adapted to be actuated by a wheel of a car in its passage 50 from the cage, means for automatically elevating the free end of said hinged track section after the withdrawal of its retaining latch, a sub-frame reciprocally suspended from said main frame, an intermediate car 55 track section carried by said sub-frame adapted to register with the sections aforesaid during the caging operation, and means for automatically elevating said sub-frame at the time of caging or discharging a car. 60

In testimony whereof we affix our signatures, in presence of two subscribing witnesses.
